UNITED STATES PATENT OFFICE.

ALBERT E. BONNEY, OF MILWAUKIE, OREGON.

CENTERING-GAGE.

1,280,379.

Specification of Letters Patent.

Patented Oct. 1, 1918.

Application filed February 20, 1918. Serial No. 218,316.

To all whom it may concern:

Be it known that I, ALBERT E. BONNEY, a citizen of the United States, residing at Milwaukie, in the county of Clackamas and 5 State of Oregon, have invented new and useful Improvements in Centering-Gages, of which the following is a specification.

This invention has reference to a centering device for lathe-works, shafting, etc., 10 and aims to produce a device of this character whereby the center of a shaft may be easily, quickly, and accurately determined and marked.

In carrying out my invention I propose 15 to produce a shaft centering gage having parallel gaging jaws provided with means for co-incidently advancing the same toward a centering tool, that is spring influenced, and which is adapted to have its 20 point forced against the end of the shaft engaged by the jaws, when said tool is subjected to an impact of force, whereby to mark the shaft at the center thereof.

The invention further consists of the features of the construction combination and arrangement of parts hereinafter fully described and claimed, reference being had to the accompanying drawings, in which,

Figure 1 is a top plan view of a centering 30 gage constructed in accordance with this invention.

Fig. 2 is a bottom plan view of the same.

Fig. 3 is a sectional view approximately on the line 3—3 of Fig. 1.

35 Fig. 4 is a sectional view approximately on the line 4—4 of Fig. 1.

Fig. 5 is a sectional view approximately on the line 5—5 of Fig. 2.

Fig. 6 is a sectional view approximately 40 on the line 6—6 of Fig. 1.

Fig. 7 is a longitudinal sectional view approximately on the line 7—7 of Fig. 1.

Fig. 8 is a detail sectional view illustrating a slight modification.

45 The improvement includes a substantially rectangular frame. The end plates for the frame are indicated by the numeral 10 and have openings through which pass the reduced threaded ends 12 of spaced rods 13, 50 the said rods providing the side members of the frame. The threaded ends 12 are engaged by nuts 14 which contact with the outer faces of the plates 10 forcing the shoulders between the rods and the reduced ends 55 thereof against the inner faces of the plates

10. In Fig. 8 of the drawings the rods 13 do not have their ends reduced, but have arranged thereon suitable sleeves which contact with the inner or confronting faces of the plates 10.

The plates 10 are each centrally provided with alining round openings 15 receiving the reduced ends 16 and 17 respectively of a screw 18. The end 16 of the screw is provided with an annular depression 19 designed to receive the end of a pin 20 which is wedged or screwed in a suitable opening 21 in one of the plates 10, and whereby the shaft is permitted rotary movement but is prevented from movement in a longitudinal 70 direction, so that the shoulders provided between the screw and the reduced ends 16 and 17 thereof need not contact with the end members 10 of the frame, and whereby unnecessary friction is overcome. The end 75 member is bent upon itself to provide a crank handle 22 whereby the screw is operated.

The threads on the screw 18, from the center thereof are pitched in opposite directions, so that the said screw is provided with right and left hand threads.

The centering tool block is indicated by the numeral 23. This block comprises a substantially rectangular member and is provided with a central transverse opening 24 and with transverse openings 25 arranged adjacent to the ends of the block. The central opening receives the screw 18 and the end openings 25 the rods 13. The block is loose upon both the screw and the rods, but is retained in proper position through the medium of headed threaded members 26 engaging in threaded openings 27 and contacting with the rods 13. The block, between one of the rods 13 and the screw 18 is provided with a centrally arranged opening or socket 28, the said opening, upon the lower or active face of the block being surrounded by a depression 29.

The centering tool is indicated by the numeral 30 and has its round shank passing through the opening 28, the lower or outer end of the said tool being enlarged or provided with a flange or collar 31 that is received in the depression 29 and rests on the shoulder provided between the depression and the opening 28. The active face of the centering tool is pointed, as at 32. To normally retain the flange or collar 31 on the 110

shoulder providing the inner wall of the depression 29, the shank of the tool, adjacent the outer end thereof is provided with a transverse opening 33 within which is arranged one end of a helical spring 34, which spring surrounds the shank of the tool and has its opposite end resting upon the upper face of the block 23.

The jaws for the device are indicated by the numerals 35, each of the same being in the nature of a flat rectangular plate. The confronting edges of the plates are formed with V-shaped notches, and the center of each of the notches is arranged in a line with the center of the pointed active end 32 of the centering tool 30.

For each of the jaws there is provided a follower block. Each of these blocks, 36, is guided on the rods 13 of the frame. Each of the blocks is provided with an additional opening for the screw 18. The threads in the openings of the respective blocks are pitched at different angles to co-engage with the respective right and left hand threads on the screw.

The jaws are supported on the blocks 36 by hollow members in the nature of sleeves 37. The sleeves for the respective blocks are of different lengths, whereby one of the jaws is elevated above the other jaw and may slide over the lower jaw when the blocks 36 are influenced by the screw to bring the same toward each other. Passing through suitable openings in the respective jaws and entering threaded openings in the respective blocks, are screw members 38 which hold the jaws on the sleeves and the sleeves on the blocks.

The tool 30 may be properly centered, with respect to the jaws, by actuating the screw to bring the jaws toward each other and the follower blocks of the jaws into contact with the opposite sides of the tool carrying block, the block 36 will be properly positioned on the frame to arrange the centering tool directly central with respect to the jaws. The block is provided with threaded openings communicating with the rods or with the openings through which the rods 13 pass through the block, and threaded members, such as screws 27 engage these openings and frictionally contact with the rods 13 to hold the block in proper position on the frame.

It is believed that the simplicity of the construction and the operation of the device

will be apparent without further detailed description.

Having thus described the invention, what I claim is:

1. A centering device comprising a substantially rectangular frame having a longitudinally arranged screw journaled in the ends thereof and said screw having one of its ends provided with a handle, the screw, from the center thereof having its threads oppositely pitched, a block on the side members of the frame and on the screw, a centering tool carried by the block and having spring means for normally retaining the same in one position, means for binding the block against the side members of the frame, centering jaws each comprising a flat plate having its inner edge notched, a block for each of the plates guided on the sides of the frame and having threaded openings receiving the oppositely pitched threads of the screw, sleeves of different lengths on the respective blocks, and elements passing through the jaws and sleeves for securing the jaws to the blocks and elevating one of the jaws above the other jaw.

2. In a device for the purpose set forth, a frame made up of end pieces and parallel rods removably connected to said end pieces, a screw having reduced ends journaled in the end pieces, one of said ends having a circumferential groove, an element carried by one of the end pieces entering the groove, the other end of the screw being cranked, said screw from the center thereof having its threads pitched in opposite directions, a tool block slidably arranged on the rods and receiving the screw, a spring influenced centering tool movable through the tool block, means for securing the tool block on the rods, follower blocks guided on the rods and engaged by the screw whereby to simultaneously move said follower blocks toward or away from each other when the screw is turned, a plate comprising a jaw for each of the blocks, sleeves of different lengths between the follower blocks and the respective jaws, securing means between said jaws and the respective follower blocks whereby one of said jaws is elevated above the other jaw, and the jaws at the confronting ends thereof having V-shaped notches.

In testimony whereof I affix my signature.

ALBERT E. BONNEY.
